STRAND FORMING DEVICE

Thomas H. Clack, San Francisco, Calif.

Application July 14, 1937, Serial No. 153,553

7 Claims.

(Cl. 28—1)

This invention relates generally to improvements in weaving looms, and has particular reference to weaving looms for the purpose of producing rag rugs, or the like.

5 The primary object of the invention is to produce a wire loom of this character that is very cheap to manufacture, and that takes the place of the usual wooden frame for this purpose, in present use.

10 Another object of the invention is the provision of a loom of the character set forth that is composed of wire spot-welded together to form the loom frame.

15 A further object of the invention is to provide a weaving loom having a spot-welded metal frame in which is included means for tensioning the cotton or hemp cord during the operation of weaving.

20 A still further object of the invention is to provide a simple weaving frame of the character set forth, that is light in construction and that may be easily and quickly produced, and is designed primarily to supplant the more expensive wooden frame at present utilized for the purpose.

25 Other objects and advantages of the invention will be apparent with reference to the subjoined specification, and the accompanying drawing, in which:—

Figure 1 is a plan view of my improved loom, 30 showing the general configuration thereof.

Figure 2 is a side view of the device turned on its end; and

Figure 3 is a rear elevation of the same.

It has been the general practice heretofore in 35 the weaving of rugs, such as rag rugs, to do this weaving on a wooden loom of a somewhat expensive and cumbersome character. These looms warp due to weather conditions, and are therefore very unsatisfactory in this respect.

40 I have therefore, produced a metallic loom, preferably constructed of wire, the sections of which are spot-welded together to form the various elements constituting the loom frame.

45 Referring more specifically to the drawing in which the preferred form of the invention is disclosed, the loom frame comprises an upper A-shaped wire frame 5, having downbent sections or legs 6, and additional sections 7 inwardly bent as indicated at 8, and a cross brace section 9.

50 A supporting loop 10 is formed at one end of the frame and is welded by an upright 11 to the main frame 5 and additional supporting loops 12 are welded to said frame at the opposite end thereof.

Spool or ball supporting spindles 13 are formed 55 centrally of the loops 12 as shown in Figures 2

and 3, and these spindles carry the spools of cotton or hemp twine, which are used in fashioning the rug.

A hook 14 is formed on the upper end of the upright 11 and tensioning loops 15 extend upwardly from the brace section 9, these parts being all welded together as a unit. 5

It will now be observed that when spools of cotton or hemp twine are placed upon the spindles 13 with a looped end thereof placed in the hook 14, 10 and the intermediate sections thereof are fed through the tensioning loops or members 15 that the device is ready for the weaving of a rug, such as a rag rug.

So called "Persian loops" or knots are formed 15 in the twine by means of small sections of rags which draw the sections of the twine together progressing from the hook 14 toward the tensioning loops 15.

When that section of the rug is formed it is 20 withdrawn from the hook 14 and moved outwardly and a new section is formed between the hook 14 and the tensioning loops 15 and this operation is continued until sufficient material is woven to form the rug.

After this material has been woven, the strip 25 is coiled and stitched to form the rug. This operation, as described, is the usual method of forming this type of rugs, and is well known in the rug weaving art.

It will thus be observed that I have provided a loom for the purpose set forth that is light in weight, is compact, and that may be cheaply constructed from ordinary wire, spot-welded together to form a compact loom frame, and one 30 that will resist varied weather conditions.

I claim and desire to secure by Letters Patent of the United States, the following:—

1. A strand forming a device of the class described, comprising a frame, a hook at one end of 40 said frame, spaced twine supporting spindles mounted on the other end of said frame, and twine tensioning means supported on the frame between said spindles and said hook.

2. A strand forming device of the class described, comprising a support, a strand supporting means at one end of said first named support, stationary twine supports fixedly mounted on the other end of said support, and spaced twine tensioning means located between said 45 spindles and said strand supporting means.

3. A device for forming a braid of textile material from strands of twine or the like comprising a frame, means supported by said frame for releasably holding the completed portion of 50

- said braid, and guide means supported by the frame for holding the strands to be braided in spaced relationship and converging toward the first of said means.
5. 4. A device for forming a braid of textile material from strands of twine or similar material comprising a frame, means supported by said frame for frictionally and releasably holding the strands for forming the braid in spaced relation to each other and in angular relation to said braid being formed, and means also supported by said frame and spaced from the first of said means for releasably holding the said braid.
10. 5. A device for forming a braid of textile material from strands of twine or the like comprising a frame, means supported by said frame for releasably holding the completed portion of said braid, at least one strand support mounted on said frame in spaced relation to said means, and tension means supported by the frame for creating tension on that part of said strand between the first of said means and said tension means and for holding the strands in spaced relation and converging toward the first of said means.
15. 6. A device for forming a braid of textile material from strands of twine and rags, or the like, comprising a substantially A-shaped frame formed of bent and welded wire, a wire hook secured substantially at the narrow end of said frame, the shank of said hook being welded to said frame, the open portion of said hook facing substantially away from the broad end of said frame, a transverse wire rigidly secured across the broad portion of said frame, tensioning devices welded to said transverse wire, said tensioning devices including two coiled pieces of wire spaced from one another, the coils of which are adapted and arranged to engage the strands of twine when said strands are passed therethrough, and two upstanding spindles also formed of bent wire rigidly secured to the broad portion of said frame.
20. 7. A device for forming a braid of textile material from strands of twine and rags, or the like, comprising a substantially A-shaped frame formed of bent and welded wire, a wire hook secured substantially at the narrow end of said frame, the shank of said hook being welded to said frame, the open portion of said hook facing substantially away from the broad end of said frame, a transverse wire rigidly secured across the broad portion of said frame, tensioning devices welded to said transverse wire, said tensioning devices including two coiled pieces of wire spaced from one another, the coils of which are adapted and arranged to engage the strands of twine when said strands are passed therethrough, and two upstanding spindles also formed of bent wire rigidly secured to the broad portion of said frame.
25. 30. THOMAS H. CLACK.
